UNITED STATES PATENT OFFICE.

LAWRENCE INNESS, OF FREEHOLD, NEW JERSEY.

BASEBALL NOVELTY.

Application filed May 9, 1927. Serial No. 190,064.

My present invention has reference to a novelty that is primarily in the nature of a plate or sign holder, but is also of a highly ornamental design and construction so that 5 the same may be employed as a paper weight on a desk as well as an ash tray.

In carrying out my invention I aim to produce what I will term a base ball novelty that shall include an ornamental base having ornamental pillars arising therefrom and connected by an ornamental column, the said pillars having on their inner faces hooks of a particular and peculiar formation and designed to suspend thereon plates bearing 10 the names of the baseball teams in a league, the name plate of the league being arranged in the corners, the name carrying plates for the teams being thus interchangeably supported so that the positions occupied by the 15 teams of the league in the different stages of the baseball season will be accurately arranged on the base of the device and further wherein the base of the improvement has a concavity therein that may be employed as 20 a pocket or holder for desk utensils or they may have arranged therein to project slightly thereabove, a combined cigar holder and ash tray.

The drawings illustrate the improvement, 25 and wherein:

Figure 1 is a perspective view of a baseball novelty in accordance with this invention.

Figure 2 is a horizontal sectional view 30 therethrough.

Figure 3 is a perspective view of one of the hooks.

As disclosed by the drawings, I make use 35 of a base 1 which is milled to provide an ornamental design. Preferably the base is formed of some suitable hard wood and is round in plan. Arising from the base, adjacent to the opposite sides thereof, there are pillars 2, of the same material from 40 which the base is formed. The pillars each preferably comprise a substantially rectangular member but its faces and its outer side are ornamented by representations of the bats employed by baseball players. The 45 pillars 2 are connected by a cornice 3 which is also highly ornamented and is of the

same material as the pillars and base. On one or both faces of the cornice 3 there is removably secured a plate 4 bearing the name of a baseball league. These plates 55 may be reversible, having the names of the different leagues inscribed on the different faces thereof.

On the inner straight faces of the pillars 2 and at equidistantly spaced points there 60 are arranged oppositely disposed pairs of hooks 5. The hooks each have an offset shank 6 which is pointed and threaded and these shanks are screwed into the pillars. The hooks 5 are designed to be 65 passed through openings 7 adjacent to the upper corners of plates 8. The plates equal in number the teams playing in a league and each of the plates has inscribed upon one or both of its faces the names of the 70 baseball clubs in the league. As the teams change places in the playing of the games the plates 8 are removed and replaced to arrange the same in accordance with the standing of the clubs in the league, that is, 75 the leading club is arranged at the top of the device, the second club next to the leader and so on.

The base 1 on its upper face is depressed to form the same with a pocket 9. This 80 pocket may serve as a receptacle for desk utensils such as pens, paper clips, etc., but if desired the base may have arranged therein a removable ash tray 10 provided on its periphery with cigar or cigarette holding lips.

The simplicity of the improvement, the ornamental thereof and the advantages of the same to a baseball enthusiast will, it is thought, be perfectly understood and appreciated so that a more detailed description is not deemed necessary.

Having described the invention, I claim:

1. In a device for the purpose set forth, 95 a base, spaced pillars arising therefrom, a cornice connecting the top of the pillars, equidistantly spaced offset hooks arranged in opposite pairs on the inner faces of the pillars, and said hooks designed for engagement through openings in the corners of data carrying plates.

2. In a device for the purpose set forth, an ornamental base, pillars arising therefrom, an ornamental cornice connecting the top of the pillars, said cornice having a removable and interchangeable indicia bearing plate thereon, equidistantly spaced offset hooks arranged in opposite pairs on the inner faces of the pillars, and data carrying plates having apertures for engagement with the hooks and designed to be suspended therefrom.
- 5
2. In a device for the purpose set forth, an ornamental base, pillars arising therefrom, an ornamental cornice connecting the top of the pillars, said cornice having a removable and interchangeable indicia bearing plate thereon, equidistantly spaced offset hooks arranged in opposite pairs on the inner faces of the pillars, and data carrying plates having apertures for engagement with the hooks and designed to be suspended therefrom.

In testimony whereof I affix my signature.

LAWRENCE INNESS.
